Des. 228,210
Patented Aug. 21, 1973

228,210

BEVERAGE DISPENSER

Clyde D. Scott, Rte. 3, Box 1837,
Fort Smith, Ark. 72901

Filed June 16, 1971, Ser. No. 153,911

Term of patent 14 years

Int. Cl. D7—99

U.S. Cl. D94—3 C

FIG. 1

FIG. 2

FIG. 3

FIG. 4

FIG. 5

FIG. 6

FIG. 1 is a perspective view of a beverage dispenser showing my new design;

FIG. 2 is a front elevational view thereof;

FIG. 3 is an end elevational view thereof;

FIG. 4 is a rear elevational view thereof;

FIG. 5 is an end elevational view, opposite to that of FIG. 3; and

FIG. 6 is a top plan view.

I claim:

The ornamental design for a beverage dispenser, as shown.
